EMIL H. A. BOLBUCK, OF LOS ANGELES, CALIFORNIA.

BRICK-KILN.

1,277,539.

Specification of Letters Patent.

Patented Sept. 3, 1918.

Application filed September 28, 1916. Serial No. 122,672.

To all whom it may concern:

Be it known that I, EMIL H. A. BOLBUCK, a subject of the Emperor of Germany, residing at Los Angeles, in the county 5 of Los Angeles and State of California, have invented new and useful Improvements in Brick-Kilns, of which the following is a specification.

My invention relates to brick kilns in 10 which a suitable number of chambers are provided for continuously burning bricks consecutively in the several chambers; and the objects of my improvements are, to provide a kiln in which the partitions can be set 15 for continuous and semi-continuous burning in the adjacent compartments; to provide a kiln in which the heat from the compartments with the burned bricks can be used in combination with the freshly turned-on burners in other compartments; the invention consisting in the construction, combination and arrangement of devices hereafter more fully described and claimed and illustrated in the accompanying drawing, in which—

Figure 1 is a horizontal section through a part of the kiln.

Fig. 2 is a slight modification of Fig. 1.

Fig. 3 is a cross section through the kiln 30 on line 3—3 of Fig. 1.

Fig. 4 is the connecting opening between two adjacent compartments having a gate for closing the opening.

Fig. 5 is a slight modification of the connecting opening of Fig. 4 having a burner 35 projecting into the opening.

Fig. 6 is a longitudinal section through the kiln on line 6—6 of Figs. 1 and 3.

Fig. 7 is another slight modification of 40 the connecting opening of Fig. 4, having a wall built in of loosely set bricks.

Fig. 8 is a cross section of the opening on line 8—8 of Fig. 7.

Fig. 9 is a slight modification of Fig. 3 45 having on top of the kiln across the same a chamber used for a furnace for indirect burning.

Fig. 10 is another slight modification of Fig. 3 having longitudinal channels in the 50 top of the kiln communicating with the cross chamber of Fig. 9.

Fig. 11 is a section through a part of the kiln on line 11—11 of Fig. 9.

Fig. 12 is a slight modification of Fig. 11.

Fig. 13 is a slight modification of the 55 burner chambers in Fig. 6.

Fig. 14 is another slight modification of the burner chambers in Fig. 6.

Fig. 15 is still another slight modification of the burner chambers in Fig. 6.

Similar numbers refer to similar parts throughout the several views.

The stationary partition walls 1 are built in crosswise with the surrounding walls 3 and 4, the outer walls 3 forming the end wall while 4 designates the side or longitudinal walls. The partitions 1, forming the compartments 5, positioned crosswise in the kiln, form also the support or bearing walls for the arch-shaped top or crown 6, above the compartments, see Fig. 6. A removable partition wall 7 is placed longitudinally through the center of the device, the partition walls 1 being transversely disposed in relation to the removable length 75 walls. A communicating door opening 8 is provided in the stationary partition walls 1, for controlling and directing the heat through the several compartments for continuous and semi-continuous burning. 80 These door openings are closed by doors 9 whenever a change in the direction of the heat is wanted.

As the material or articles to be burned in such brick kiln require different heatings, 85 some articles requiring a slow heating and burning, while other articles allow a quick heating; this kiln is constructed to allow the necessary changes to burn articles disposed in this kiln just as required. For treating 90 articles of the class to be burned slowly, movable partitions are provided to be set so as to compel the gases to pass through the several compartments one after another, while for treating articles which allow a 95 quicker burning, movable partitions are provided to be set so as to allow the gases to burn in several compartments at the same time and pass through several other compartments in a continuous manner thereby 100 bringing all material in all the compartments of the whole kiln under heat soon after the kiln has been started and set ready for burning. Having constructed a kiln with a suitable number of stationary partitions to insure a good construction for supporting the arch-shaped top or crown of 105 such kiln and having also provided a suitable number of openings in these stationary partitions, this makes it possible to use movable partitions in such a manner as to allow the heating in the manner described above.

In Fig. 1 this kiln is illustrated with movable partitions inserted into the openings of the stationary partitions for a slow burning.

5 Starting the burner in the compartment 10, the heat is directed through the compartment 11 on the opposite side of the kiln, passing through the door opening 12 over to the compartment 13, farther through 10 the door opening 14 into the compartment 15, through the door opening 16 over to the compartment 17 and so forth.

The door openings can be closed by suitable doors temporarily, and as the center 15 wall 7 is also temporarily built in while setting the bricks in the several compartments, this kiln is constructed to allow a continuous burning of the bricks in the different compartments as well as a semi-continuous 20 burning, (under "continuous" it being understood that the several compartments in the kiln are communicating in such a manner as to cause a burning of the bricks in the kiln in one compartment succeeding 25 one other compartment in following order until the bricks in all compartments are burned at which time the first compartments will have been built up again and the burning continues in the following compartments 30 in a succeeding order; while under "semi-continuous" it being understood that two or more compartments are set so that the burning occurs in a parallel order and the whole kiln is divided into 35 several sets, each of similar proportion as the first set of parallel burning compartments, two, three, or more, and the several sets of parallel burning compartments are interconnected so as to burn parallel in a 40 succeeding order) which will be described below in reference to Fig. 2, which is a slightly modified figure of the Fig. 1. But it will also easily be understood that more chambers or compartments can be burned 45 in this kiln by suitable setting of the temporary partitions and doors.

Of course, starting in the compartment 10 with the burning of the bricks, it is necessary to close the lower left-hand opening 50 8 in Fig. 1 by a temporarily built in door.

In Fig. 2 is a slightly modified construction, instead of the continuous burning described above in connection with Fig. 1, there is a semi-continuous burning, the kiln 55 being the same as illustrated in Fig. 1 with the same stationary partitions but having movable or temporary partitions placed in a different manner for the burning of articles which allow a quicker burning.

60 In this construction the communicating door openings are closed in a different manner than in Fig. 1. Going out from the compartment 18, the next compartment 19 is started at the same time. The communicating door openings 20, 21, 22 and 23 are

closed by suitable doors, directing the heat from the compartments 18 and 19 the full way across the kiln into the compartments 24 and 25. The compartments 18 and 19 form in this construction of Fig. 2 really 70 one compartment with the opposite compartments 24 and 25, as the removable partition wall 7, shown in Fig. 1 is not used in this modified construction of Fig. 2. From the compartments 24 and 25, the heat 75 is directed through the door openings 26, 27 and 28 into the compartments 29 and 30, again passing the whole way across the kiln into the opposite compartments 31 and 32.

It will easily be understood that with 80 these communicating door openings, it is possible to burn even more than two compartments at the same time, and still, any number of compartments started at the same time can again be controlled and burned 85 continuously with another similar number of compartments, following the first started number of compartments, this making the device adaptable for continuous burning as well as for semi-continuous burning. 90

The burners 33, see Fig. 6, are inserted from the top into combustion chambers or furnaces.

Each compartment is provided with a suitable number of such combustion chambers and furnaces and when such compartments are set ready for burning after a suitable length of time for drying the material or articles in such combustion chambers, the material or articles are put under direct 100 heat from such burners inserted from the top of each compartment. 105

The flues 34, see Fig. 3, are longitudinally embedded in the crown of the kiln. Small connecting flues 35 connect these main 110 flues 34 with the furnaces 36. In case that the heat from a compartment with burned bricks shall be used in another compartment, perhaps at the other end of the kiln, the heat from the first compartment with the 115 burned bricks is directed through the main flues 34, whence it is taken by opening the corresponding gate valve or damper 37 in the connecting flue 35 allowing the heat to pass over through the furnace 36 into the desired compartment by way of the downwardly directed flue 38, see Fig. 6.

Each furnace is communicating with one of the compartments by a downwardly directed flue 38 and each one of the furnaces 120 comprises an independent chamber normally open at the top having one or more burners directed into the opening, but, using the heat from other compartments, the opening of the furnaces for the burners are closed 125 up and the damper 37 close to that furnace is opened letting in the heat from other compartments through the furnace directing this heat into the compartment close to and communicating with that furnace. 130

If the heat procured by the burners inserted through the top of a certain compartment is not wanted in other compartments, this, as also the waste heat is directed through the waste flues 39 provided in the floor of the kiln, whence it is drawn off through the flues 40 into the main waste 41.

The flues and connecting openings, it will be understood, can be closed or covered so as to direct the heat and gas in the kiln in the desired direction.

To prevent the heat from passing straight through the communicating door openings, 15 and to obtain a better circulation, baffles 42, being walls of suitable height, are disposed before the door openings.

The baffles are perforated on the lower end allowing heat to pass into the compartment from below through these perforations and over the top edge of the baffles, this causing a whirling and circulation of the heat-wave through the compartments.

The burners 33 are placed in combustion 25 chambers or furnaces allowing direct burning of the bricks as well as more indirect by having flash walls 45 provided, into which the flames from the burners are directed, see Figs. 1, 2 and 3. The flash walls 30 are built up of loosely set bricks allowing the heat to pass through the whole kiln which has been opened and set for burning.

The communicating door openings are closed by gates 46 as indicated in Fig. 4. 35 The doors 9 are temporarily built in of the same bricks when setting new bricks in the different compartments thereby forming a continuous or semi-continuous kiln or any other form desired and possible in this construction of kiln, while the gates 46 are disposed in permanently constructed slots or spaces. The gates 46 are a slightly modified construction for closing the door openings. Other slightly modified constructions 45 of the shutting off of two adjoining compartments are illustrated in Figs. 5, 7 and 8. In Fig. 5, a burner is disposed so as to allow the injecting of a strong flame into the space of the door opening, preventing the cool air in one compartment from entering or passing over to the adjoining heated compartment. In this construction it is not necessary to close or even have a door between the cool compartments and the compartment in which the burning is started, 55 as the draft is naturally going in the direction from the started compartment through the brick burning compartments, and, any cool air passing through the strong flame disposed in the first door opening will naturally be warmed and heated before it reaches the bricks in the burning compartments without being able to do any damage to the bricks in the burning compartments.

60 In Fig. 7, the door opening is built up with

loosely set bricks 47 forming a hollow wall, as indicated at 48 on Fig. 8, which can be filled up with sand or other suitable material through the opening 49 from the top.

The waste flues 40 are shut off in a suitable manner, the gate valves or dampers 50 being spaced to allow a sand filling to be filled in to give a good tight closure, see Fig. 3.

The furnaces 36 of Figs. 3 and 6 are 75 slightly modified in the Figs. 9, 10, 11, 12, 13, 14 and 15. In Fig. 9, the furnace 51 is formed on top of the kiln, crosswise over the whole width of the kiln.

In starting the burning of the kiln, it will 80 naturally be necessary to allow air to pass near the burners into the furnaces, but after the bricks in any of the compartments are done, the heat from that compartment is directed through flues 52 into the furnaces 85 51, and the furnaces in such a case are closed as indicated at 53, the burners 33 being disposed in the closures 53. The heat from the furnaces passes through the flues 54 into the kiln. While Fig. 11 illustrates a section 90 through the flues being placed on top of the kiln as described in Figs. 9 and 10, in Fig. 12 is a slight modification, having the furnaces embedded in the top or crown 95 6 of the kiln.

In Fig. 13 is a slight modification of the furnaces in Fig. 6, the furnaces 36 of Fig. 6 being connected by a small flue 55.

In Figs. 14 and 15 are slight modifications of the top furnaces of Figs. 9, 10 100 and 11. The furnaces illustrated in Fig. 14 being a combination of the furnaces embedded in the crown of the kiln as illustrated in Fig. 13 and the furnaces placed on top of the kiln as in Figs. 9, 10 and 11. 105 The furnaces in Fig. 15 are slightly modified as each flue 54, going into the kiln has a separate furnace 56.

Operating this kiln for burning articles which require a slow burning, the burners 33 110 of the compartment being started first are ignited first and the heat from these burners is directed into that first compartment, the articles in this compartment first drying and later on burning as required. If no other 115 compartment is connected or ready for burning, the heat from this first compartment is passed out of the waste flues 39 in the bottom of the compartment and further through flues 40 and 41.

Having other compartments ready for burning under the same slow process, the heat from the first compartment is directed through one of the openings at the end of the first compartment communicating with 125 the second compartment in the manner described above. After first drying the articles in the second compartment, (in Fig. 1 it would be compartment 13) and after these articles in compartment 13 have been dried 130

enough to stand greater heat, the burners in the top of the compartment 13 are ignited and burn in the same manner as the compartments 10 and 11, all this heat passing 5 through the baffles 42, through the opening 14 into the compartment 15 for first drying the articles in compartment 15 making them also ready for a greater heat of burning in the same manner as the articles in the compartments 10, 11 and 13, while the burners are inserted through the top of the compartment 15. This slow process of burning is continued through all the compartments in the kiln.

15 For burning articles which allow a quicker burning this same kiln is used and the burners in the top of several compartments are ignited at the same time and the heat therefrom is directed through these compartments 20 and through an equal number of following compartments in a similar way as described above.

For burning articles in a slow or quick manner in compartments on the opposite 25 ends of a kiln one compartment on one end being started first while another compartment on the other end of the kiln is to be burned next, then the flues 34 are used for drawing off the heat from the first compartment on one end of the kiln to the other compartment on the other end of the kiln instead of drawing the heat off through the waste flues 39 in the bottom of the compartments as described above.

30 35 Having thus described my invention, I claim:—

1. In a kiln stationary partitions and movable partitions disposed in the kiln in relation to each other forming a suitable number of compartments having communication in a succeeding order as well as in a parallel order when the movable partitions are so set 40 in relation to the stationary partitions.

2. In a kiln stationary partitions having

intercommunicating door openings forming 45 a suitable number of compartments, the compartments having communication in a succeeding order as well as in a parallel order through the intercommunicating door openings when the material disposed in the several compartments for burning is so set.

3. In a kiln stationary partitions having intercommunicating door openings, and movable partitions disposed in a suitable number of the said door openings forming a kiln burning through the several compartments in a succeeding order as well as in a parallel order when the movable partitions are so set in the intercommunicating door 55 openings of the stationary partitions.

4. In a kiln having a suitable number of compartments formed by stationary and temporary partitions adapted to form a continuous and semi-continuous kiln when so desired by suitably setting of the temporary partitions, a suitable number of independent furnaces communicating with the different compartments having gas burners disposed therein, main flues disposed in the walls of the kiln having communicating flues connecting with the furnaces, dampers disposed in the communicating flues, baffles arranged within the compartments directing the heat and gas for circulation through the bricks set in the compartments, outlet flues formed 70 in the lower part of the kiln having also dampers disposed therein, the furnaces and gas burners being arranged to inject the heat from above while the outlet flues are arranged to draw the waste heat off from 75 below.

In testimony whereof I hereunto affix my signature in the presence of two witnesses.

EMIL H. A. BOLBUCK.
